UNITED STATES PATENT OFFICE.

DON N. THOMPSON, OF SYRACUSE, NEW YORK, ASSIGNOR TO PASS & SEYMOUR INC.
OF SOLVAY, NEW YORK, A CORPORATION OF NEW YORK.

ELECTRIC SWITCH.

Application filed May 26, 1922. Serial No. 563,881.

To all whom it may concern:

Be it known that I, DON N. THOMPSON, a citizen of the United States, and a resident of Syracuse, in the county of Onondaga and

5 State of New York, have invented a certain new and useful Electric Switch, of which the following is a specification.

This invention relates to electric switches, and has for its object a switch which is particularly simple, compact and economical in construction; readily mountable on a face plate or other support; and highly efficient and durable in use. It consists in the novel features and in the combinations and constructions hereinafter set forth and claimed.

In describing this invention, reference is had to the accompanying drawings in which like characters designate corresponding parts in all the views.

20 Figure 1 is an elevation of this switch.

Figure 2 is a vertical sectional view, the contiguous part of a supporting wall or face plate being also shown.

Figure 3 is an inner face view of the base.

25 Figure 4 is a sectional view on line 4—4, Fig. 1, having the supporting plate in plan.

This switch comprises generally, a base having a pair of contacts spaced apart, a movable switch member rotatably mountable in the base and having yielding terminals for coacting with the contacts and an operating member for the switch movable into and out of engagement with the switch member upon a rotary movement of the op-

35 erating member, and a cover for the base in which the operating member is supported and by which the switch is attached to a wall, face plate or other support.

1 designates the base which is formed of 40 insulation and here shown as cap shaped. 2 are the contacts mounted on diametrically opposite walls of the base.

3 designates the switch member which is 45 rotatably mounted in the base, it being here shown as a floating switch member, that is, it is held and guided in the base by reason of the engagement of its terminals with the contacts or with the walls of the spaces between the contacts.

50 The switch member here illustrated comprises yielding terminal arms 4 and an intermediate transverse or diametrically extending portion 5, the switch member here illustrated being formed of a single strip

55 of metal bent Z-shaped in general form, the

heads of the Z forming the contact arms 4 and the intermediate part of the Z the transverse or diametrical portion 5 of the switch.

The contacts 2 and also the walls 6 between the contacts are arranged in arcs having different centers from the axis of the switch member 3, these contacts 2 and the faces 6 forming a square shaped figure having slightly curved sides. The advance ends 60 of the contacts 2 are located farther from the axis of the switch member than their other or rear ends with respect to the direction of rotation of the switch mechanism, and also preferably, the advance ends of the 65 faces 6 of the walls between the contacts are located farther from the axis of the switch member than their ends. That is, the contacts 2 and faces 6 curve slightly toward the 70 axis of the switch member.

The base is also formed with cam faces 7 and 8 from the rear ends of the contacts 2 and faces 6 respectively with respect to the direction of rotation of the switch member 3, the switch member being rotatable to the 75 right. This arrangement of the contacts 2 and faces 6 causes the switch arms to be tensioned so that when the ends of the switch arm reach the cam faces, said arms are by reason of their tension and the incline of 80 said faces, given a quick break and make or snap action in case the operator releases the handle of the switch too soon so that arcing is prevented.

The contacts 2 are provided with projections as ears 9 to which the service wires 10 are connected, these projections being here shown as lying in recesses 11 formed in the bottom of the base, and the wires as extending through the bottom. A suitable washer 12 of insulation is placed on the bottom of 85 the base to cover the recesses 11.

13 is the operating member for the switch, it being here shown as comprising a body having a shank 14 of insulation, the body being metal having an axial recess in its inner end into which the shank 14 extends and to which it is secured by indenting as at 15. The shank 14 extends beyond the end of the body into the base and is provided with 90 means for detachably engaging the switch member 3 by an axial movement of the operating member 13.

As here shown, the shank 14 is formed 95 with a diametrically extending slot 16 in its 100

inner end which forms said end bifurcated and the bifurcated end is arranged astride the transverse portion 5 of the Z-shaped switch member.

5 The operating member 13 is also provided with a handle 17 at its outer end, this handle threading on a reduced stem 17^a. 18 is a washer of insulation slidably mounted on the operating member and resting on the top 10 of the base 1 closing the top of the recess enclosed by the base.

19 is a cap enclosing the base and having a top wall 20 provided with an upwardly extending neck 21 in which the operating member is journaled, the neck being preferably riveted to the top wall at 22.

As illustrated, the top wall is formed with outwardly projecting flanges or lugs 23 lying against the periphery of the neck. The neck 20 is also formed with an internal annular shoulder 24 at its upper end against which a shoulder on the operating member thrusts to prevent outward movement of the operating member and the head or handle 17 of the operating part thrusts against the outer end face of the neck.

25 is a nut threading on the neck against the plate 26 on which the switch is supported, the nut having an annular recess 27 for receiving the lugs 23 or the ends projecting through the plate 26. Usually, a lock nut or ring 28 also threads on the neck against the nut 25.

The plate 26 is in most instances thin sheet 35 metal as brass, and it is oftentimes a cover or canopy. In applying the switch to the plate or canopy a circular hole 26^a is cut in the plate or canopy for receiving the neck 21, the hole having diametrically opposite 40 notches 26^b for receiving the lugs 23. When the nut 25 with the annular recess 27 is screwed down on the plate, the lugs prevent undue warping and bending of the plate, especially when the ends of the lugs 45 strike the bottom of the annular recess 27.

Preferably, the cap entirely encloses the base. The cap is locked to the base in any suitable manner, here shown as by a key 29 extending diametrically through openings 50 30 in the cap and lying in the diametrical groove 31 in the bottom face of the base.

In assembling, the switch member 3 is placed in the base 1 on the washer 12, the handle 17 of the operating member 13 removed and the body of the operating member inserted into the neck 21 from the interior of the cap 19, the nuts 25, 28 secured on the neck and the head or handle 16 secured onto the stem 17 of the operating 60 member 13.

To attach the switch to the plate 26 or

other support the head or handle 16 and nuts 25, 28 are removed, and the neck 21 of the cap 18 in which cap the base is assembled is inserted through the opening 26^a in 65 the plate 25, the lugs 23 also extending through the notches 26^b. The nut 25 is then turned on the neck against the plate 26, the lock nut 28 then screwed tightly against the nut 25, and lastly, the handle 16 threaded 70 on the stem 17.

What I claim is:

1. A switch comprising a cup shaped base having contacts on its inner annular wall, a cover closing the open end of the base, a 75 casing enclosing the top and sides of the base and being open at its bottom, the casing holding the cover of the base in position, a rotary switch member rotatably mounted in the base having resilient terminals for co- 80 acting with said contacts and guiding the switch member in its rotary movement, the switch member having a shank extending through the cover and through the casing, said switch member being removable through 85 the outer end of the cup shaped base upon removal of the base from the casing and the cover from the base.

2. A switch comprising a base, a cap enclosing the base having an opening in its top and an upwardly extending lug, an exteriorly threaded neck secured to the top in said opening, the lug lying along the neck, a switch member movably mounted in the base, an operating member having a shank 95 extending through the neck and connected at its inner end to the switch member, a nut threading on the neck, and having an annular recess in its advance side for receiving the lug, substantially as and for the purpose 100 set forth.

3. A switch comprising a base, a cap enclosing the base having an opening in its top and an upwardly extending lug, an exteriorly threaded neck secured to the top in 105 said opening, the lug lying along the neck, a switch member movably mounted in the base, an operating member having a shank extending through the neck and connected at its inner end to the switch member, a nut 110 threading on the neck, and having an annular recess in its advance side for receiving the lug, in combination with a supporting plate having an opening for the neck and a notch for the lug, substantially as and for 115 the purpose described.

In testimony whereof, I have hereunto signed my name, at Syracuse, in the county of Onondaga, and State of New York, this 3rd day of May, 1922.

DON N. THOMPSON.
